ADJUSTING DEVICE

Theodore Kopelman, Scranton, Pa.

Application March 14, 1934, Serial No. 715,387

5 Claims. (Cl. 2-237)

This invention relates to garments. It is particularly directed to a device for adjusting the size of a garment such as trousers, vest or the like.

5 An object of this invention is to provide an adjusting device of the character described, adapted to lie substantially flat, and not be bulky or have loose ends, and which shall be provided with a buckle permanently held onto the garment by 10 two pieces of cloth.

A further object of this invention is to provide an improved, strong and durable adjusting device of the character described, which shall be economical to manufacture, simple to operate, and 15 yet practical and efficient to a high degree.

Other objects of this invention will in part be obvious and in part hereinafter pointed out.

The invention accordingly consists in the features of construction, combinations of elements, 20 and arrangement of parts which will be exemplified in the construction hereinafter described, and of which the scope of application will be indicated in the following claims.

In the accompanying drawing, in which is 25 shown one of the various possible illustrative embodiments of this invention,

Fig. 1 is an elevational view of a portion of a garment provided with an adjusting device embodying the invention;

30 Fig. 2 is a cross-sectional view taken on line 2-2 of Fig. 1;

Fig. 3 is a view similar to Fig. 2 but showing the adjusting device taken in; and

Fig. 4 is a side elevational view of a pair of 35 trousers provided with my new adjusting device.

Referring now in detail to the drawing, 10 designates a portion of a garment provided with an adjusting device 11 embodying the invention. For the purpose of illustration only, the garment 40 10 is shown as an upper edge portion of a pair of trousers, and is provided with a horizontal seam 12 and vertical seams 13 and 14, for example, one of the usual side seams of the trousers and one of the seams which extends to one of the 45 rear pockets.

My improved adjusting device 11 comprises a strap 15 having the ends thereof stitched to the trousers by said seams 13 and 14. The length of said strap 15 is preferably substantially equal 50 to the width of the piece of cloth 16 which said strap overlies. Slidably received on said strap 15 is a buckle 17 having top and bottom portions 18, side portions 19 and 20 and a central portion 21 parallel to said side portions. The central 55 portion 21 contacts the rear or inner surface of

the strap, whereas the side portions 19 and 20 contact the front surface of said strap. The side portion 19 is preferably provided with teeth 22 on the inner edge thereof inclined rearwardly and adapted to bite into the strap 15.

Attached to one end of the strap 15, as by the seam 14, is one end of a looped piece of cloth 25, disposed between said strap and the piece of cloth 16. The meeting ends of said loop may be attached together, and to the garment by said 10 seam 14. The loop receives the central portion 21 of the buckle 17 and tethers said buckle to the garment. Said loop 25 is of less length than strap 15, for the purpose hereinafter appearing.

In Fig. 2, the adjusting device 11 is shown entirely let out. To take in the device 11, the portion of the strap on the side of the buckle adjacent loop 25 is pulled to the right while the buckle is held, whereby the strap is pulled through said buckle. Such relative movement 20 of the buckle on the strap is permitted since the teeth 22 of the buckle point in the same direction as the strap is pulled. Return movement of the strap through the buckle is prevented, however, because of the teeth biting into the strap. 25 Upon pulling the strap to the right, through the buckle 17, the distance between the seams 13 and 14 shortens, as clearly illustrated in Fig. 3, thus taking in the garment.

To let out the garment, the strap is manipulated to disengage the same from the teeth 22 and permit movement of said strap through the buckle to the left.

It will now be understood that the strap 15 can be taken in until the buckle contacts the seam 13. 35

The strap 15 is in one piece and since the ends thereof are attached to the garment at the seams 13 and 14, there are no ends presented which would require finishing. The adjusting operation is extremely simple, it merely being required 40 to slide the buckle relative to the strap in one direction or the other, depending upon the adjustment desired. The outer ends of the strap 15 need not be perfectly aligned as there are no loose ends to be interengaged. The buckle is 45 held by both the strap 15 and loop 25, thus insuring against loss of the buckle should either said strap or loop tear.

When the adjusting device is not in use, the strap 15 lies flat and there are no loose hanging 50 ends. Furthermore, overlapping strap portions are eliminated with my improved construction, preventing bulkiness.

Although the drawing illustrates a portion of a pair of trousers, it will be understood that my 55

improved construction may be incorporated into any garment which encircles part of a body, such as a waist, vest, glove, boot or the like garment. The adjusting device may be provided at both sides of the trousers.

It will thus be seen that there is provided a device in which the several objects of this invention are achieved, and which is well adapted to meet the conditions of practical use.

10 As various possible embodiments might be made of the above invention, and as various changes might be made in the embodiment set forth, it is to be understood that all matter herein set forth or shown in the accompanying drawing, 15 is to be interpreted as illustrative and not in a limiting sense.

Having thus described my invention, I claim as new and desire to secure by Letters Patent:

1. In a garment having spaced seams which 20 secure portions of the garment together, a strap permanently attached at both ends thereof by said seams to spaced portions of said garment, a single buckle slidable on said strap, said buckle having two spaced sidebars overlying said strap, and a central bar underlying said strap, and a central bar underlying said strap, and a strip of material underlying said strap and shorter than the latter having one end connected to said central bar and its other end permanently attached by one of said seams to the garment 25 adjacent one end of said strap.

2. In a garment having spaced seams which 30 secure portions of the garment together, a strap permanently attached at both ends thereof by said seams to spaced portions of said garment, a single buckle slidable on said strap, said buckle having two spaced sidebars overlying said strap and a central bar underlying said strap, and a strip of material underlying said strap and shorter than the latter having one end connected to said central bar and its other end permanently 35 attached by one of said seams to the garment adjacent one end of said strap, the sidebar of said buckle which is more remote from the point of attachment of said strip to the garment than the other sidebar having teeth directed toward said central bar and adapted to engage said

strap to prevent unintentional movement of the buckle toward said point of attachment.

3. In a pair of trousers having the usual side seam extending down the leg portion and the usual seam extending to a rear pocket, a strap having both ends thereof attached to the trousers by said seams, a buckle slidable on said strap, said buckle having two spaced side bars overlying said strap and a central side bar underlying said strap, and a strip of material underlying said strap and shorter than the latter connected to the central bar of said buckle and permanently attached to the trousers of one of said seams. 10

4. In a pair of trousers having the usual side 15 seams extending down the leg portion and the usual seam extending to a rear pocket, a strap having both ends thereof attached to the trousers by said seams, a buckle slidable on said strap, said buckle having two spaced side bars overlying said strap and a central side bar underlying said strap, and a strip of material underlying said strap and shorter than the latter looped around the central bar of said buckle and stitched to the trousers by one of said seams. 20

5. As a new article of manufacture, in combination, a garment having a seam, stitching uniting the portions of the garment at the said seam, a take-up strap appliance carried by said garment, and comprising an outer strip one end of which is attached to the garment by the 25 stitching at the seam and the other end of which is attached also to the garment, a buckle having a cross bar intermediate its ends and openings at opposite sides of the cross bar through which said outer strip is threaded so as to lie at one 30 side of the cross bar, and an anchor member for 35 said buckle comprising an inner strip folded to form an approximately U-shaped loop and having its ends united to the garment by the stitching at the said seam, the intermediate portion 40 of said anchoring means or member passing around and receiving the cross bar of the buckle, and one of the end bars of the buckle adjacent to said cross bar being formed with engaging 45 parts to engage the said outer strip of the take-up strap. 45

THEODORE KOPPELMAN.
